ATTORNEYS

UNITED STATES PATENT OFFICE.

JOSEPH HAMILTON MARLIN, OF BLOOMINGTON, INDIANA.

MOLE-TRAP.

SPECIFICATION forming part of Letters Patent No. 359,454, dated March 15, 1887.

Application filed August 10, 1886. Serial No. 210,544. (No model.)

To all whom it may concern:

Be it known that I, JOSEPH HAMILTON MARLIN, a citizen of the United States, residing at Bloomington, in the county of Monroe and State 5 of Indiana, have invented certain new and useful Improvements in Mole-Killers; and I do declare the following to be a full, clear, and exact description of the invention, such as will enable others skilled in the art to which it 10 appertains to make and use the same, reference being had to the accompanying drawings, and to letters or figures of reference marked thereon, which form a part of this specification.

15 Figure 1 of the drawings is a representation of my invention, and is an elevation of the same. Fig. 2 is a vertical section. Fig. 3 is a vertical section.

20 My invention relates to mole-traps or mole-killers; and it consists in the construction and novel combination of parts, as hereinlater described, and pointed out in the claims.

25 Referring by letter to the accompanying drawings, A designates a hollow staff of any convenient length, in which staff is inclosed a spiral spring, B, which spring may be compressed by pulling upon the cross-bar C near the middle portion of the spike E, said cross-bar working in the vertical trans- 30 verse slots F F in the lower end of the staff A. Said slots F F extend up some distance into the staff A. The spring B encircles that portion of the spike E above the cross-bar, the lower end of said spring bearing against the 35 upper edge of the cross-bar C, the upper end of said spring B bearing against the material of the staff at the upper end of the bore G of the staff, said bore commencing at the lower end of the staff, and extending above the upper 40 ends of the slots F F far enough to permit the spike E to be raised to draw the point of the spike up into the lower end of the bore of the staff.

Near the upper ends of the slots F F are 45 pivoted the triggers H H', their lower ends, I I', being bent or curved so that said lower ends will pass under the projecting ends of the cross-bar C when the upper ends of the triggers H H' are set under the upper hook 50 ends, H², of the sliding trip-rods K K', said trip-rods being bent at L below the hook ends of the triggers H H', so that these hook ends will

be turned out of the way of the cross-bar C when the spike E is projected by the spring B. At their lower ends the trip ends K K' 55 are provided with rings or feet M formed thereon by bending the wire of the trip-rods in oval shape. When the trip is set, the hooks of the triggers engage the under edges of the projecting ends of the cross-bar C, and the upper 60 ends of the triggers are engaged by the hooks on the upper ends of the sliding trip-rods.

The two angularly-bent prongs P P' in the lower end of the staff are inserted into the ground directly in front of the moles, and as 65 the mole passes between the prongs it first raises one trip-arm and releases the trigger on that side, and as the head of the mole passes beneath the other trip-arm its body is directly under the spike, and as the second trip-arm is 70 raised the second trigger is released and the spike is shot down by the spring and passes directly through the body of the mole, impaling the mole on the spike, and thus killing it.

Having described this invention, what I 75 claim, and desire to secure by Letters Patent, is—

1. The combination, with the slotted staff provided with the axial bore in its lower portion and the fixed prongs projecting from its 80 lower end, of the spike arranged in the bore and having the cross-bar intermediate of its ends, the encircling-spring around the spike above the cross-bar, and the pivoted trigger adapted to engage the cross-bar, and sliding 85 trip-rod at one side of the staff adapted to engage the upper end of the said trigger, substantially as specified.

2. The combination, with the slotted staff provided with the axial bore in its lower portion and the fixed prongs projecting from its 90 lower end, of the spike arranged in the bore and having the cross-bar intermediate of its ends, the encircling-spring around the spike above the cross - bar, the pivoted triggers 95 adapted to engage the cross-bar, and sliding trip-rods on opposite sides of the staff adapted to engage the trigger, substantially as specified.

In testimony whereof I affix my signature in presence of two witnesses.

JOSEPH HAMILTON MARLIN.
